(57) **CLAIM**

The ornamental design for a wireless handheld communication device, as shown and described.

DESCRIPTION

FIG. 1 is an isometric view of the wireless handheld communication device;

FIG. 2 is a different isometric view thereof;

FIG. 3 is an elevated plane view of a front side thereof;

FIG. 4 is an elevated plane view of a back side thereof;

FIG. 5 is an elevated plane view of a left side thereof, the right side thereof being a mirror image of the left side;

FIG. 6 is an elevated plan view of a top side thereof; and,

FIG. 7 is an elevated plan view of a bottom side thereof. The features shown in broken lines are for illustrative purposes only and form no part of the claimed design.
